INTERLOCKED GRATING

Louis Norman Lumb, Long Island City, N. Y., assignor to Irving Iron Works Company, a corporation of New York

Application June 24, 1932, Serial No. 619,078

11 Claims. (Cl. 94—8)

This invention relates primarily to the armor-
ing of pavements and floors by the use of a cheap,
light weight grating which is more or less flex-
ible along lines transversely of its mesh, but is
5 also sufficiently self-sustaining for transporta-
tion from factory to job location, if it is desired
to follow that procedure, or can be assembled on
the job from the constituent elements. When
assembled in panel form it can be placed
10 on properly spaced apart supports and is then
capable of maintaining its shape and sustaining
the weight of workmen, forms for concrete filling,
and vehicles needed for transporting such con-
crete or other plastic cement mixture to the vari-
15 ous points on the surface of the grating at which
such concrete or cement is to be dumped.

Another object of the invention is to produce
a grating of the honeycomb or reticuline type
which can be assembled on the job without rivet-
20 ing or bolting or welding, being composed of
standard weight metal strips crimped and cut in
the shop to a uniform wave-like outline and inter-
locked on the job. Such strips, if desired, can be
shipped in bundles from the plant to the job
25 location and there interlocked to form the grating
without requiring the use of tools other than a
hammer employed for forcing such strips to-
gether in interlocking relation each with the
others.

30 Still another object is to produce, in the above
described manner, out of relatively short bent
strips a substantially continuous grating of uni-
form mesh and of indefinite length and breadth
which shall have nearly uniform strength at all
35 points for resisting stresses tending to bend it
about any axis extending transversely of the
longer dimensions of its meshes, and so serve as
a continuous surface armoring for concrete pav-
ing and floorings. Its other objects and advan-
40 tages will be hereinafter pointed out or be obvi-
ous on a more detailed explanation of the inven-
tion.

The best embodiment of the invention, at
45 present known to me, is illustrated in the ac-
companying sheet of drawing in which

Fig. 1 is a plan view of a strip of concrete
pavement with parts broken away and my im-
proved grating used as a surface armoring there-
50 for.

Fig. 2 is a perspective detail view of one of the
interlocked joints between adjacent strips shown
on an enlarged scale with parts broken away.

Fig. 3 is a similar view of the members of an-
55 other joint, the parts being separated to show the

complete outline of each at and adjacent to the
joint, and

Fig. 4 is a cross section on line 4—4 of Fig. 1,
also shown on a larger scale.

Throughout the drawing like reference charac- 60
ters indicate like parts.

The essential structure of the grating is com-
posed simply of a plurality of metal strips, prefer-
ably of uniform length and depth, each of which
has been crimped or bent to a substantially uni- 65
form wave-like outline and provided with means
for interlocking the adjacent wave crests of suc-
cessive strips when the latter are assembled side
by side.

For purposes of description the various bent 70
strips shown in Fig. 1 may be divided into two
classes, those of one class being marked A1, A3
and A5 and being so arranged that they have
tongues 1, 1, cut out of each wave crest and pro-
jecting upwardly, while those of the other class 75
marked B2, B4 and B6 have similar tongues 2, 2,
projecting downwardly, as best shown in Fig. 3.
Two connected panels are illustrated in Fig. 1, the
ends of strips similarly marked, as A1, A3, A5, in
the several panels abutting when the panels are 80
joined together end to end, as do also the strips
similarly marked B2, B4 and B6.

All of said strips, however, have the same form
so that each one is produced by the same series
of crimping and punching operations applied to 85
strips of the same length, and the differences
above noted result merely from turning one set of
strips, as B2, B4, B6, upside down with reference
to the other set A1, A3, A5, when each panel of
the grating is being assembled. 90

These tongues 1 and 2 could be otherwise formed
than by cutting them out of the strips A and B
as shown, but the essential feature of the inven-
tion is that each strip shall be provided at the
crest of each of the successive waves of the out- 95
line into which it has been crimped with a tongue,
or other engaging means, by which it may be
interlocked with the oppositely disposed engaging
means on the crest of any of the waves of any
adjacent strip which may have such tongues or 100
interlocking means projecting in the opposite di-
rection. Preferably, however, these tongues are
made integral with the strips and are formed by
simply notching each strip at points adjacent
the ends of each wave crest, as shown at 3, 3, to 105
a depth one half of the entire depth of the strip
when it is set on edge and consequently to a depth
one half that of the grating formed when a plu-
rality of such strips of uniform depth are assem-
bled and interlocked one with another by the 110

- hooking of the tongues on each strip over, or under, those on the adjacent strips.
- Preferably each of the tongues 1 and 2 has a circular perforation 4 of uniform size, the center of which is located midway of the length of the tongue and midway of the depth of the strip, so that when the tongues are interlocked, as shown in Fig. 1, by hooking one over the other, the holes 4, 4, in each set of wave crests arranged transversely of any panel of grating so formed will all lie in one and the same straight line so that a keying rod 5 can be pushed through the holes to lock all the strips together, and also to give the panel a certain degree of stiffness against forces tending to bend it about an axis extending longitudinally of said panel.
- If all strips are of uniform depth and are notched as above described, their upper edges will then lie in one plane and their lower edges in another plane parallel to the first, thus forming a perfect panel of honeycomb or reticuline grating without the use of rivets or other fastening means, unless the rods 5, 5, are employed to give the panels the additional stiffness above described.
- If a continuous grating or armoring is to be used each strip preferably terminates at each end in a half wave crest length 6 and the end edge of the strip has a semicircular notch 7 formed therein so that when two such ends abut a circular hole is thereby formed of the same diameter as the holes 4, 4, in the tongues 1 and 2, and as a result every two such abutting half wave crest lengths 6, 6, form a composite tongue which has the same configuration as the one piece tongues 1 and 2, and is therefore adapted to interlock with them if oppositely disposed, as best shown in Fig. 2. The keying rods 5, 5, or other keying means, then pass through the circular openings formed by the registering, semicircular notches 7, 7, in the abutting ends of any two corresponding strips A1, A1, or B2, B2, &c. in the successive assembled panels of grating, and also through some of the holes 4, 4, in other strips and thus lock the successive panels together, as shown in Fig. 1, if the strips of one class, as A1, A3, in each panel are staggered endwise with reference to those of the other class B2, B4, &c. so that the ends of strips of one class project at one end of the panel and those of the other class at the other end of the panel.
- If separate panels are to be used at the ends of which all strips are to be connected together, each strip should then be given a full wave crest end portion 8 with a hole 4 in it so that all these free ends can be securely keyed together by a rod 5 or other keying means. Such an arrangement is shown at the left hand end of Fig. 1, and where successive panels are keyed together end to end to form a long grating or armoring, the end panels of each such assembly should have their outer ends formed as above described. To produce this result one set of strips in such end panel, as A1, A3, &c. would be made a half mesh length longer than the other set B2, B4, &c. so that the other ends of the longer set will project beyond those of the shorter set one half mesh length at the other end of the panel to form the desired interleaved joint with the next panel. All the intermediate panels of the grating assembly would, however, be formed of strips of even length so that each such panel end would have half its strips, as A1, A3, &c. projecting a half mesh length at one end and the strips of the other set B2, B4, &c. projecting such half mesh length at the other end of the panel. Panels

of this type would be successively connected end to end until the other extremity of the particular grating assembly is reached, when a final panel, (not shown) of strips of different lengths but reversing the arrangement shown at the left hand end of Fig. 1 is employed. Thus a grating or armoring assembly would be produced, the strips at the ends of which would all have a full wave crest length enabling them to be securely keyed together by a rod 5 or other fastening means.

A grating thus formed will present at all joints between successive panels a certain resistance to bending around any axis extending transversely of the panel due to the half mesh length interleaving of the strips which are keyed together at points a half mesh length apart, and this power of resistance can be heightened by extending the interleaving arrangement for a distance greater than a half mesh length by extending or increasing the staggering of some or all of one set of strips with reference to the other set to the desired degree.

Also the outside strips, as A1, can be made longer than the strips in the interior of the grating so as to leave fewer exposed butt joints such as shown at 9 in Fig. 1 and the same procedure could be followed with the strips forming the other side edge of the grating assembly.

If the tongues 1 and 2 are formed by notching the edges of the strips at 3, 3, as shown and above described, a locating of these notches at the proper points slightly removed from the full crest of each wave section automatically produces the necessary slight offsetting of each of the two engaging tongues so as to enable them to slip easily but closely one behind the other when the strips are assembled for mutual interlocking. Such arrangement is clearly shown in Fig. 3. If the notches 3, 3, are formed by punching out portions of these strips, the burr left on the edges of the notches will serve as a friction means for holding the strips in interlocked relation after they have been forced together, as shown in Fig. 2.

An important use of the grating above described is in the formation of a cheap, light weight armoring for the surface of concrete panels and continuous roadways, as indicated in Figs. 1 and 4, where 10 represents a concrete filling poured and set in and/or under the mesh of the grating. It might also be possible to first form the concrete surface and then roll the armoring into it before it sets.

Among the obvious advantages of the invention may be mentioned the following: The strips comprising it being of uniform length and outline (with the possible exception of the few required for the end panels) can be made in quantity by a standardized operation in the shop, each originally straight strip being cut the same length, punched to form similar holes 4, 4, and notches 3, 3, all uniformly spaced apart, and each strip having similar end notches 7, 7. The latter could be formed by making the strips a little longer than the length required for the finished article, punching holes 4 near the ends of each strip and then cutting off said strip ends along lines passing transversely through the centers of said holes. The punched strips so formed are then uniformly crimped on a simple set of dies, the holes 4, 4, serving to accurately register each wavecrest in such dies, and then the finished strips can be bundled together like fagots and transported to the job location. On the job the strips are interlocked to form the grating by simply turning every other one upside down and

driving the members of one set into engagement with those of the other set after causing notches 3, 3, to register. This can be done with a hammer or even by the workman stamping on the assembled strips with his heels. The desired number of rods 5, 5, are then inserted and the job is complete if only a grating is to be produced. If the grating is to be used as armoring, the concrete is added. If desired the assembly of each panel 10 can be done on the bench at the shop and only the interlocking of successive panels performed on the job. If the foundation is somewhat uneven and it is desired to have the grating adjust itself thereto, the keying rods 5 may be omitted 15 and the grating will then be flexed within limits to fit the foundation much as a sheet of chain mail adjusts itself to the body of the wearer. On the other hand, a strong, self-supporting grating can be formed by using a sufficient number 20 of transverse rods 5, 5, thus producing a structure which will support a considerable moving or stationary weight when resting on spaced apart bearings and maintain a smooth, even, plane surface at all times.

25 A minimum cost of production results from the low cost of materials, absence of waste materials and small amount of labor required. Special splices and cutouts can be made by the workmen on the job with the use of a hack saw 30 to cut the desired number of strips to the desired length. All handling of small rivets, bolts and nuts is avoided and the interlocked joints form an excellent bond for the concrete filling as do also the transverse rods 5 which are wholly 35 merged in concrete.

Various changes could be made in the details of construction above described without departing from the principle of the invention so long as the novel arrangement of parts and interaction thereof are preserved wholly or in part.

Having described my invention, I claim:

1. The combination of two sets of similarly bent strips of wavelike outline adapted, when assembled, to form a grating of substantially uniform mesh, the members of one such set having tongues formed at their upper edges at all points of contact with members of the other set and projecting upwardly in the planes of the respective wave crests out of which they are formed, and the members of such other set having similar tongues formed at such points of contact but projecting downwardly in the planes of the respective wave crests out of which they are formed; whereby said two sets of tongues may 50 be interlocked one set behind the other throughout the entire lengths of each pair when a plurality of such members are assembled side by side and intermeshed, the members of one set alternating with the members of the other set.

60 2. A combination such as defined in claim 1 in which said tongues are cut in the edges of the respective strips and conform to the wave outline of the strip of which they form parts, but are separated from the adjacent edge portions of said strip by slots cut therein at points slightly offset laterally from said tongue portions and all said cuts extend to one half the depth of the strip, so that the slots in each strip intermesh with those of its neighbor as their respective tongues are 70 slid one behind the other in assembling the grating.

75 3. As a new article of manufacture a grating such as defined in claim 1 in which certain of the tongues in each strip are centrally perforated, combined with a plurality of rods passing through

said holes in said tongues which are in line one with another transversely of the grating.

4. As a new article of manufacture a grating such as defined in claim 1 in which certain of the tongues in each strip, are centrally perforated, combined with a plurality of rods passing through said holes in said tongues which are in line one with another transversely of the grating, and in which the end tongues of each strip are half the length of the others and are provided with semi-circular end notches registering with similar notches in the ends of abutting strips.

5. As a new article of manufacture a grating such as defined in claim 1 in which certain of the tongues in each strip are centrally perforated, combined with a plurality of rods passing through said holes in said tongues which are in line one with another transversely of the grating, and in which the end tongues of each strip are half the length of the others and are provided with semi-circular end notches registering with similar notches in the ends of abutting strips and all strips are of uniform lengths, the butt joints between strips of one set being staggered with reference to those between strips of the other set; whereby interleaved joints between abutting panels of the grating are produced.

6. A grating which is slightly flexible along transverse lines which comprises the combination of a plurality of strips of metal of uniform depth, each bent to a substantially uniform, wave-like outline, and assembled side by side with the crests of the waves interlocked one with another by intermeshed, vertically extending tongues, all said interlocked tongues being of uniform size and each having a depth equal to one-half the depth of the strip, and having uniformly located perforations at their bases, together with fastening members extending through said perforations; whereby the joints so formed are free from clamping pressure sufficient to produce rigidity, but are securely pinlocked.

7. A continuous grating comprising essentially, in combination, a plurality of strips of metal of uniform length each bent to a substantially uniform wavelike outline, which strips are assembled in groups side by side with the crests of the waves in each group interlocked by oppositely projecting, overlapping, vertically extending tongues, the ends of the strips in each group abutting the ends of the strips in an adjacent group or groups and each being formed of half a tongue section, and the strips in each group being similarly staggered endwise each with reference to its neighbors; whereby the pairs of abutting ends between groups are staggered longitudinally of the grating, thereby breaking joints, and are each keyed together by a wave section of a staggered strip intermeshed therewith, thereby connecting together successive groups of strips.

8. A grating such as defined in claim 9 in which one set of strips forming each end panel are half a mesh longer than the strips of the other set and have their exposed ends of full wave crest length; whereby they may be conveniently fastened together to form even ends for the grating assembly.

9. A continuous grating comprising, in combination, an assembly of a plurality of strips of metal of uniform depth, each having a wave-like outline with tongues formed in one edge of each strip at each wave crest by notches cut near the extremity of each such crest and extending to a depth of substantially one-half of the depth of the strip in which they are cut, one set of alternate strips in said assembly having their said tongues

- all pointing in one direction, and the other set of alternate strips having their said tongues pointing in the opposite direction, and said two sets of strips being intermeshed, the tongues of one set 5 engaging and extending behind the entire length of the tongues of the other set and the notches in one set completely engaging those in the other set.
10. A grating such as defined in claim 9 in 10 which the central portion of each wave crest in
- said strips is provided with a hole of uniform outline, combined with a plurality of keying members inserted in said holes.
11. A grating such as defined in claim 9 in 80 which the central portion of each wave crest in said strips is provided with a hole of uniform outline combined with a plurality of rods extending transversely of the grating through said holes from one side to the other thereof.
